US00D457858S

(12) **United States Design Patent** (10) Patent No.: **US D457,858 S**
Lee (45) Date of Patent: ** May 28, 2002

(54) **POWER SUPPLY DEVICE FOR REMOTE CONTROLLER**

(75) Inventor: **Il Yeul Lee**, Seoul (KR)

(73) Assignee: **Shinwoo Tech Co., Ltd.**, Choongjoo-si (KR)

(**) Term: **14 Years**

(21) Appl. No.: **29/134,302**

(22) Filed: **Dec. 20, 2000**

(30) **Foreign Application Priority Data**

Jun. 20, 2000 (KR) 00-15887

(51) LOC (7) Cl. **13-02**

(52) U.S. Cl. **D13/110**

(58) Field of Search D13/110, 123, D13/162, 164; 307/64, 150, 151; 363/141

(57) **CLAIM**

The ornamental design for power supply device for remote controller, as shown and described.

DESCRIPTION

FIG. 1 is a perspective view of a power supply device for remote controller showing my new design.

FIG. 2 is a front elevational view;

FIG. 3 is a rear elevational view of FIG. 2;

FIG. 4 is a left side elevational view of FIG. 2;

FIG. 5 is a right side elevational view of FIG. 2;

FIG. 6 is a top plan view of FIG. 2; and,

FIG. 7 is a bottom plan view of FIG. 2.

1 Claim, 2 Drawing Sheets

FIG. 1**FIG. 2****FIG. 3**

FIG. 4**FIG. 5****FIG. 6****FIG. 7**
